Miles Pratt's Design for top & bottom plates of Air-tight Stoves
No. 195 Fig. 1

Fig. 2.

Fig. 3.

3028

Specification re U.S. Patent No. 1126, Boston.

Dec. 195

Abelias Pratt, Barre, Mass. ⁱⁿ Cotton Patent No. 195
Dated August 15, 1848

The schedule referred to in these Cotton Patent and
making part of this same.

To all persons to whom these presents shall come:—
Be it known, that Abelias Pratt of Barre in the County of
Plymouth State of Massachusetts have invented and produced

2

Dec. 195

and diamonds carved on each; between which two rings is the
ribbed ring. N. N.

The several ornaments are represented clearly in detail, in
Figs 1 & 3, and the whole exterior face of both the top and
bottom plates, is covered with what is known as the lace
pattern as shown at 0.0. in said figures.

Having thus described my new design I shall state my
claim as follows

What I claim as my invention, and desire to have secured
to me by letters patent, is, the combination of the several
mouldings, ornamented as herein above described, con-
sisting of my improved designs for the top and bottom
plates of a cylindrical air tight stone
